FENCE SECTION OR THE LIKE

Allen Brook Gallion, Ellicott City, Md.

Application July 28, 1955, Serial No. 37,173

Term of patent 14 years

(Cl. D28—2)

Fig. 2 is a fragmentary perspective view taken from the rear and left of Fig. 1;

Fig. 3 is a sectional view taken along line 3—3 of Fig. 1; and

Fig. 4 is an enlarged fragmentary view of one of the fence panel members, a part being broken away for convenience of illustration.

I claim:

The ornamental design for a fence section or the like, as shown.
